UNITED STATES PATENT OFFICE

169,589

TETHERED TOP TOY

Merrill L. Hassenfeld, Providence, R. I.

Application April 18, 1951, Serial No. 14,881

Term of patent 3½ years

(Cl. D34—15)

To all whom it may concern:

Be it known that I, Merrill L. Hassenfeld, a citizen of the United States, residing at Providence, in the State of Rhode Island, have invented a new, original, and ornamental Design for a Tethered Top Toy, of which the following is a specification, reference being had to the accompanying drawing, forming part thereof.

In the drawings:

Fig. 1 is a perspective view of a tethered top toy, showing my new design, with the top released from the holding means;

Fig. 2 is a side elevational view thereof showing the parts in assembled position;

Fig. 3 is an end elevational view thereof; and
Fig. 4 is a top plan view thereof.

The handle shown in broken lines is partially broken away for convenience of illustration.

The dominant features of my new design are shown in solid lines.

I claim:

The ornamental design for a tethered top toy, as shown and described.

MERRILL L. HASSENFELD.
